By O. D. Seward,

Attorney.

UNITED STATES PATENT OFFICE.

KING LOUIS KARO, OF WASHINGTON, DISTRICT OF COLUMBIA.

CONVERTIBLE TRUNK.

SPECIFICATION forming part of Letters Patent No. 391,621, dated October 23, 1888.

Application filed September 20, 1888. Serial No. 285,887. (No model.)

To all whom it may concern:

Be it known that I, KING LOUIS KARO, of Washington, in the District of Columbia, have invented certain new and useful Improvements 5 in Convertible Trunks; and I do hereby declare the following to be a full, clear, and exact description of the invention, such as will enable others skilled in the art to which it app pertains to make and use the same.

10 My invention relates to an improvement in convertible trunks.

The object is to provide a trunk which may be converted into a bureau, convenient for use in traveling, and in which an outer casing of 15 the trunk shall serve to protect the trunk when being shipped and afford additional storage-room when the trunk is set up as a bureau in the room.

15 A further object is to provide a top with mirror-holding guides or supports, so that the mirror may be set up and removed at pleasure.

With these ends in view my invention consists in certain features of construction and combinations of parts, as will be hereinafter 25 described, and pointed out in the claims.

In the accompanying drawings, Figure 1 is a view of the convertible trunk as it appears when being shipped. Fig. 2 shows the same partially set up as a bureau, and Fig. 3 shows 30 the same completely set up and the door opening into the auxiliary storage-room open.

A represents the inside casing of the trunk, the ends and back of which are preferably made solid, while the front is made in skeleton frame-work style to admit drawers, a, of 35 various widths and depths to suit the requirements of a packing or traveling trunk. The inside casing has an outer casing, consisting of a front, B, and ends C, hinged thereto at their 40 lower edges, so as to admit of being folded over downwardly into vertical positions, as shown in Fig. 3, forming a support for the inner casing. The ends of the front B are preferably constructed to project past in front of the edges 45 of the ends, and are provided with rearwardly extending flanges or lips b, which serve, when the parts are folded, to overlap and snugly secure the ends at the corners, and when the front is turned downwardly said lips form an edge 50 finish around the base of the bureau at the front. Thus when the front and ends are turned down and the trunk set up against the wall there will

be formed the storage-chamber, inclosed on its front and ends by the said front and end casings, B and C, which chamber is a convenient 55 receptacle for soiled clothes, shoes, &c. Access to this auxiliary storage-room thus formed is obtained by a panel, b', in the front B, which is conveniently hinged to the front on the inside and held in position by any well-known 60 and simple catch; or, when hinged as shown in the accompanying drawings, its own weight will hold it closed.

The top D is hinged at the back, and is provided with a depending flange or lip, d, which 65 is adapted, when the top is closed, to project down over the upper edges of the front and ends and lock them firmly in position. Said top is also provided on its under side with grooves or holders d', secured thereto or formed 70 integral therewith, and arranged to receive a mirror, E, when the cover is raised.

When the trunk is closed for travel, the mirror may be removed and packed in position within the trunk, where there will not be so 75 great liability of its being broken. There is also a stationary top, D', which, when the cover is raised, forms a bureau-top, and this may be recessed, as shown at G, to receive the mirror-holder. A lock, F, of any well-known or ap 80 proved construction, is employed to secure the cover to the front.

It will be observed that the front B and ends C, as well as the top D, serve, when the trunk is being shipped, as protections to the inner 85 casing, forming, together with the interior casing, a double wall around at least four faces of the trunk, and that when set up as a bureau three of these protective casings form, in conjunction with the wall of the room, an inclosed 90 storage-chamber, while the top supports the mirror.

The whole is as free as may be from complications, and forms a convenient and quite inexpensive combination, while it possesses great 95 strength to protect it against injury by rough handling on the road.

It is evident that slight changes might be resorted to in the form and arrangement of the several parts described without departing from the spirit and scope of my invention; hence I do not wish to limit myself strictly to the construction herein set forth; but,

Having thus fully described my invention,

what I claim as new, and desire to secure by Letters Patent, is—

1. In a convertible trunk, the combination, with an inner casing provided with storage compartments, of outer casing-sections at the front and ends, hinged at their lower edge to the inner casing, and forming, when swung into depending position, a storage-chamber closed at the front and ends, and a door in one of the sections to gain access to the storage-chamber, substantially as set forth.

2. In a convertible trunk, the combination, with an inner casing, of outer front and end

casings hinged to the inner casing, a stationary top, and a swinging top, the swinging top 15 having a mirror-holder on its under side, and the stationary top having a recess to receive the holder, substantially as set forth.

In testimony whereof I have signed this specification in the presence of two subscribing witnesses.

KING LOUIS KARO.
